BRACE HOLDER AND PRESS

Martin Bonato, Santa Barbara, Calif.

Application July 30, 1936, Serial No. 93,509
Renewed December 15, 1937

1 Claim. (Cl. 144—104)

The invention relates to a drilling brace press and more especially to a combined brace holder and press.

The primary object of the invention is the provision of a device of this character, wherein a drill brace can be conveniently held in working position with respect to a piece of work to be drilled and such brace can be fed or pressed to the work for the proper drilling thereof, the device being of novel construction and will assure the proper pressure upon the brace during the drilling period for the successful drilling of a piece of work.

Another object of the invention is the provision of a device of this character, which is simple in its make-up, thoroughly reliable and effective in its operation, convenient for the handling of the brace, assuring the proper feeding of the bit to the work, strong, durable, and inexpensive to manufacture.

With these and other objects in view, the invention consists in the features of construction, combination and arrangement of parts as will be hereinafter more fully described, illustrated in the accompanying drawing, which discloses the preferred embodiment of the invention and pointed out in the claims hereunto appended.

In the accompanying drawing:

Figure 1 is a side elevation partly in section of the device showing the drill brace fitted therein.

Figure 2 is a sectional view on the line 2—2 of Figure 1.

Figure 3 is a sectional view on the line 3—3 of Figure 2.

Similar reference characters indicate corresponding parts throughout the several views in the drawing.

Referring to the drawing in detail, the device comprises a base or bed 5, in this instance flat and has rising from its heel side thereof a crane or upright 6 provided with a forwardly directed upper end 7. This end 7 is formed with a guide head 8 through which works a vertically disposed toothed rack 9 acted upon by a feed gear 10. The gear 10 has its journal 11 which is fixed thereto passed through the side walls of said guide and to one side of the guide is a ratchet gear 12, the same being fixed to the journal 11 for a purpose presently described.

The rack 9 at its lower end has coupled at 13 therewith for free swivel movement a clamping head 14 for accommodating the terminal handle knob 15 of a brace 16, the head 14 being split at 17 at intervals to permit of the bending of such head about the handle knob 15 of said brace as is clearly shown in Figure 1 of the drawing.

The knob 15 when engaged in the clamp 14 will suspend the brace 16 from the rack 9 while

the chuck 18 of this brace carrying the drill 19 will have bearing on a rest bracket 20, it being suitably perforated at 21 for the passage of the drill 19 therethrough. The bracket 20 is slidably fitted on a vertically disposed guide rod 22 fastened to the crane or upright 6 in the bed or base 5. Beneath the bracket 20 and about the guide rod 22 is a coiled compression spring 23 so that after the bracket is moved downwardly under pressure applied to the brace 16 in the 10 operation thereof, it will be returned to inoperative position as said pressure is relieved.

About the ratchet wheel 12 and freely supported on the journal 11 is a press handle 24 fitted with a pawl or dog 25 for engaging the ratchet wheel 12. The said pawl or dog 25 has its stem 26 slidably fitted in the handle 24 and about this stem is a compression spring 27 which biases the pawl or dog 25 into engagement with the ratchet wheel 12 for the locking of the handle 20 therewith. The spring 27 plays against a finger or hand operated piece 28 fitting the outer end of the stem 26 and projected from the outer end of the handle 24. The piece 28 is operated to release the pawl or dog 25 from the ratchet wheel 12 so that the handle 24 can swing independently of this wheel and also have the adjustment of such handle so that the rack 9 can be turned to exert pressure upon the brace 16 downwardly for the feeding of the bit 19 in a piece of work operated upon thereby for the boring of such work, the bracket 20 yielding to the pressure applied to the brace 16 against the resistance of the spring 23.

The brace 16 can be raised and lowered by the handle 24 through the coaction of the gear wheel 10 meshing with the rack 9. The base or bed 5 is formed with a clearance 29 for the drill or bit 19 when boring through the work during drilling operation to avoid damage to the drill or bit when 40 passing through the work and avoiding its contact with the bed or base 5 in the use of the device.

What is claimed is:

A brace holder and press comprising a base, a crane rising from the base and having a forwardly directed upper end, a guide head on the forwardly directed upper end, a vertically disposed toothed rack fitting said head, a feed gear journaled in said head and meshing with said toothed rack, a ratchet acting lever arranged with the head and active upon the feed gear for the turning of the same, a coupling carried by said rack at its lower end, and a bit brace knob receiving head swiveled to the rack by said coupling and having splits at intervals for the bending of the head about the brace knob for its clamping thereby and suspension of said brace from the rack.
